WRIST WATCH REGULATOR

Frank Suttin, Los Angeles, Calif.

Application June 19, 1944, Serial No. 541,082

5 Claims. (Cl. 58—112)

1

This invention relates to adjusting means for the regulators of watches, and is particularly useful when applied to the regulators of diminutive watches such as ladies' wrist watches.

The regulator itself consists of a small pivoted pointer on the regulator plate, the point of which is movable along a scale. Movement in one direction accelerates the watch movement, and in the other retards it.

One of the objects of this invention is to provide adjusting means for engaging the tip of the regulator, that will enable a micrometer effect to be attained when making a regulator adjustment, that is to say, to enable very minute or nice adjustments to be made; and to accomplish this without increasing substantially the amount of space occupied by the regulator adjusting mechanism above or beyond the face of the regulator plate, on which this mechanism is mounted. This enables this regulator to be used in very thin watches.

The invention involves the use of a threaded bar or adjusting screw along which a traveller or nut is moved in effecting an adjustment of the regulator, and one of the objects of this invention is to provide a mounting for this adjusting bar that will operate to hold it quite close to the face of the regulator plate.

Further objects of the invention will appear hereinafter.

The invention consists in the novel parts and combination of parts, to be described hereinafter, all of which contribute to produce an efficient wrist watch regulator.

A preferred embodiment of the invention is described in the following specification, while the broad scope of the invention is pointed out in the appended claims.

In the drawing:

Fig. 1 is a plan view of a regulator plate illustrating a regulator provided with adjusting means embodying my invention.

Fig. 2 is a side elevation of the plate and regulator, but showing the nut, the adjusting bar and its mounting in section on the line 2—2 of Fig. 1.

Fig. 3 is a section through the body of a bracket that I prefer to employ, and showing one of the ears or supports for the adjusting bar. This section is taken about in the plane of the line 3—3 of Fig. 1. Fig. 4 is an end view of the bracket shown in Fig. 3, showing the preferred form of the other end of the bracket.

Fig. 5 is a side elevation of the supporting bracket.

Fig. 6 is a fragmentary elevation illustrating a modified embodiment and mounting for the ears that support the adjusting bar.

Referring to the parts, the regulator 1 is illustrated as mounted in the upper face of the regulator plate 2 in the usual manner and its tip 3 sweeps along a scale 4 attached or formed on the face of the plate. In doing so it swings about its pivot 5 that attaches it to the plate.

10 In applying my invention, I provide bracket means preferably comprising a frame bar 6, attached by any suitable means such as with screws 7, and provided at its ends with integral ears 8 and 9.

15 The ears 8 and 9 afford means for holding the adjusting bar or screw 10 in position adjacent to the face of the plate. In order to accomplish this I provide sockets in the two ears. One or both of these sockets are in the form of an open socket or notch 11, as illustrated in Fig. 4.

20 In order to hold the projection of the parts to as low a level as possible above the face of the plate the ears project laterally from the frame-bar 6. This enables the nut 12 that rides on the bar to lie directly on the face of the plate instead of lying on the face of the frame-bar 6.

25 In the present instance I have illustrated the ear 8 as provided with a socket 13 of round form to receive the end of the adjusting bar, and at this point the adjusting bar may have its diameter reduced to form a pintle 14 that fits loosely in the round socket 13.

30 At its other end the adjusting bar 10 is formed with a neck 15 of reduced diameter, that fits into its socket 11, and thereby a shoulder 16 is formed to engage the inner face of the ear 9. This shoulder cooperates with a corresponding shoulder 17 seating against the ear 8 to prevent the adjusting bar from shifting longitudinally in the ears.

35 An end of the adjusting bar or screw 10 may be provided with a head such as a screw head 18 for enabling the bar to be rotated to move the nut to or fro. The side of this nut adjacent to pivot 5 has a driving connection to the regulator. This connection is constructed so that movement can be imparted through it in either direction at all times, and preferably consists of a notch 19 the side faces of which have the involute form employed in forming a rack tooth, so that this notch becomes virtually a "tooth space," and the tip of the regulator is formed with a head 20, with involute curved side faces to engage the side faces of the notch like a tooth of a gear meshes with the teeth of a rack. By reason of

this correlated form of the head 20 and the faces of the notch 19 an effective contact is maintained between the regulator and the driving nut throughout a sufficient distance along the screw 10 to insure that sufficient adjusting movement can be accomplished to meet all requirements in regulating the watch.

It is not essential to my invention to employ the frame bar 6 to connect the ears 8 and 9. If desired the ears may be made as separate pieces (see Fig. 6) in which one of the ears 8a is illustrated as being made of a small angle form clip with a shoulder 8b to engage the edge of the plate 2a to assist in properly aligning this ear. A single fastening, such as the screw 8c may be employed for securing the ear to the plate. The opposite ear would be attached to the plate 1a in a similar manner.

However, it is highly advantageous to employ the frame bar 6, and in providing the ears 8 and 9 so that they extend laterally from the frame bar. This not only enables the regulator screw to be rotatably supported nearer to the upper face of the regulator plate 2, but it also facilitates removal and replacement of the adjusting screw 10 without necessitating complete removal of the frame bar 6 to do this. This facility arises from the fact that the bearing 11 not only is in the form of a socket open on its side toward the plate, but (as indicated clearly in Figure 4) the wall of this socket on the side remote from the frame bar does not extend all the way down to the face of the plate. In this way a gap is formed under this wall through which the reduced neck 15 on the adjusting screw can be shoved laterally into or out of position, in other words, by loosening up the fastening 7 the regulator screw can be removed or replaced without having to completely remove the frame bar. Furthermore, by having the fastening screws 7 out of line with the adjusting screw in the completed construction it is possible to enlarge the gap referred to by tilting the frame bar so that the outer ends of the ears 8 and 9 rock further away from the face of the regulator plate. And the fact that the ears 8 and 9 provide bearings for the adjusting screw that are disposed laterally from it avoids the necessity for slotting the regulator plate to enable the assembly of the frame bar and ears carrying the adjusting screw and nut to be attached to the regulator plate.

Other embodiments of this invention may be made without departing from the spirit of the invention.

I claim as my invention:

1. In a regulator adjustment for a diminutive watch such as a wrist watch, the combination of a regulator plate, a regulator with a pivot on said plate and lying substantially against the face of said plate, a nut lying on said plate and having a threaded opening therethrough; an adjusting screw passing through said nut and engaging in said threaded opening; bracket means supported on the plate and supporting the said screw; and a driving connection between said nut and the tip of said regulator including involute surfaces on

the nut and regulator maintaining contact for imparting movement from the nut to the regulator in either direction at all times, located on the side of the nut that lies adjacent to said pivot.

5. 2. A regulator according to claim 1 in which the said driving connection includes a socket in the side of the nut receiving the tip of said regulator.

10 3. In a regulator adjustment for a diminutive watch such as a wrist watch, the combination of a regulator plate, a regulator with a pivot on said plate and lying substantially against the face of said plate; a nut lying on said plate and having a threaded opening therethrough; an adjusting screw passing through said nut and engaging in said threaded opening; a bracket having a frame bar lying on the regulator plate and having an ear projecting laterally from the same at each end, one of said ears having a circular bearing for receiving the end of the adjusting screw, and the other ear having a socket opening toward the plate, the wall of said socket on the side remote from the frame bar terminating short of the face of the regulator plate, so as to leave a gap between it and the face of the plate; and fastening means including a screw passing through the frame bar to secure the same on the regulator plate, said adjusting screw having a neck of reduced diameter facilitating its passing into line with said socket by a lateral movement through said gap and under the last named ear from the side opposite to said frame bar.

15 4. In a regulator adjustment for a diminutive watch such as a wrist watch, the combination of a regulator plate, a regulator with a pivot on said plate and lying substantially against the face of said plate, a nut lying directly against the outer face of said plate, and having a threaded socket therethrough, an adjusting screw having threads 20 engaging the threads in said socket, bracket means having a frame bar lying on the outer face of the regulator plate, fastening means passing down through the bar for securing the same to the regulator plate, said frame bar having laterally extending ears thereon, having bearings for supporting said regulator screw, said bearings including a bearing opening on the under side toward the regulator plate.

25 5. In a regulator adjustment for a diminutive watch such as a wrist watch, the combination of a regulator plate, a regulator with a pivot on said plate and lying substantially against the face of said plate; a nut lying on said plate and having a threaded opening therethrough; an adjusting screw passing through said nut and engaging in said threaded opening; bracket means supported on the plate and supporting the said screw; and a driving connection between said nut and the tip of said regulator, including an involute surface on the regulator cooperating with the nut for maintaining contact with the same to impart movement from the nut to the regulator in either direction at all times, said driving connection located on the side of the nut that lies adjacent to said pivot.
